VENTILATING AND CONDITIONING
SYSTEM

Willis H. Carrier, Essex Fells, and John H. Holton, Maplewood, N. J., assignors, by mesne assignments, to Carrier Corporation, Newark, N. J., a corporation of Delaware

Application April 5, 1935, Serial No. 14,812

3 Claims. (Cl. 98—38)

This invention relates to air conditioning, and more particularly to a method of and means for positively ventilating conditioned enclosures.

In the art of conditioning enclosures, it is general practice to recondition and recirculate air withdrawn from the enclosure, adding to the recirculated air a quantity of fresh air sufficient to meet the physiological requirements of the occupants, to prevent the atmosphere of the enclosure from becoming vitiated and odoriferous, and to compensate for air losses through doors, windows and the like. Under certain conditions, however, systems heretofore in use have failed to add the requisite quantity of fresh air to the recirculated air, the atmosphere of the enclosure becoming unhealthy and unpleasant in consequence.

The rate of air flow established by a fan, blower or other draft device is determined in part by the static pressures existing on the intake and exhaust sides of the device. Thus, when a fan moves air from a point on the intake side of the fan to a point on the exhaust side of the fan, it will move a greater volume of air per unit time if the static pressures at both points are the same than if the static pressure of the point on the intake side is below that of the point on the exhaust side. So also, a fan device which draws separate volumes of air from two sources of supply at the same static pressure will continue to draw such air volumes in fixed proportion only so long as the static pressures at the sources remain unchanged; if the static pressure of one source of supply should fall, the fan would draw less air from that source, a correspondingly greater amount of air being drawn from the other source of supply. If it be assumed that a fan device supplying air to an enclosure draws air from within the enclosure and from outside the enclosure in desired proportions, it will be apparent that any fall in the outside static pressure will cause an unbalanced condition in which an insufficient quantity of outside air is supplied to the enclosure.

Such a condition of unbalance might obtain, for example, when the wind blows against a building, the fresh air intake being on the sheltered or leeward side thereof, for it is well known that an area of negative pressure is developed on the leeward side of an obstruction to the rapid flow of air. So also, a condition of unbalance of outdoor and indoor static pressures results from "stack effect", whenever the indoor air is warmer or colder than the outside air.

It is the general object of the invention to

provide a system of and means for ventilating and conditioning an enclosure assuring a positive supply of outdoor air to the enclosure to be conditioned.

It is another object of the invention to draw 5 gases from two sources of supply in substantially constant volumetric ratio, notwithstanding variations in the static pressures of said sources of supply.

It is another object of the invention to withdraw a volume of air from an enclosure to be conditioned, to add thereto a desired volume of fresh air and to discharge the resultant mixture into the enclosure.

Still another object of the invention is to provide 15 means for supplying fresh or outdoor air from a single point of supply to a plurality of conditioning units positioned in and/or serving a plurality of enclosures.

A further object of the invention is to provide 20 an air conditioning and ventilating system with which desired atmospheric conditions within an enclosure may be obtained at all times, and which will be relatively simple, practical, efficient and inexpensive.

A feature of the invention resides in the provision of a fresh air fan in combination with a return air fan, said fans cooperating to supply to an enclosure a mixture of fresh and return air in substantially fixed proportions at all times. 30 A feature of the invention resides in drawing air from an area of substantially constant static pressure, drawing other air from an area of variable static pressure, mixing the air drawn from each of said areas to form a mixture of substantially constant proportions, and supplying 35 the mixture to an enclosure.

A further feature of the invention resides in the introduction of fresh air into the conditioning unit at a point beyond the return air fans, 40 and in such a manner that substantially all of the fresh air is subjected to the conditioning action of the unit.

Still another feature of the invention resides in the provision of sound-absorbing means in 45 combination with the fresh air fan, whereby quiet operation of the apparatus is assured.

Other objects and features of the invention, including advantages in design, construction and operation, will be apparent from the following 50 description, to be read in connection with the accompanying drawings, in which:

Fig. 1 is a front elevational view, partly in section, of one form of the invention, showing 55 the conditioning unit and the fresh air intake

unit, and the general assembly of the units within a decorative outer casing;

Fig. 2 is a section through the conditioning unit, taken on the line 2—2 of Fig. 1, showing the return air intake and the fresh air distributing duct;

Fig. 3 is a section through the fresh air intake unit, taken on the line 3—3 of Fig. 1, illustrating the manner in which the unit may be connected to a partially opened window;

Fig. 4 illustrates an alternative form of the invention in which a two-stage ventilating fan is utilized.

Referring now to the drawings, and considering particularly Figs. 1—3, numeral 10 designates generally a casing housing the conditioning unit 11 and the fresh air intake unit 12. Fans 13 of the unit 11 are suitably driven, as by motor 14, and draw air from the enclosure through the grille 15 of the casing 10 and through a filter 16 of any desired type, discharging it upwardly through the unit. When humidification is required, water is fed to nozzle 17 through supply pipe 18 and is impinged against target 19, whereby it is distributed throughout the unit as fine spray, readily to be taken up by air passing through the unit. Plates 45 serve to distribute the recirculated air throughout the unit and to prevent the drainage of excess spray water into the fan scrolls. Such water collects in the channels 46 of plates 45 and is delivered to sump 23.

Partition 20, extending throughout the length of the unit 11, divides the upper part of the unit into two passageways. In one of these are positioned the conditioning coils 21, of the finned or other desired type, which may be supplied with refrigerant during the warmer periods of the year, or with steam, hot water or the like for heating during the colder periods of the year. If desired, of course, separate heating coils and cooling coils may be provided. In the other passageway are positioned the eliminator plates 22, the function of which is to remove entrained spray water from air passing therethrough. Such water, or water condensed from the air by coils 21 when cooling and dehumidification are effected, falls into sump 23, whence it may be disposed of in any desired manner, as by drainage through outlet 24. Dampers 25 control the proportions of air passing through the conditioning coils and through the bypass.

Fresh air is supplied to the unit 12 through the duct 26. The outdoor opening of this duct may be positioned in accordance with engineering expedience. For purposes of illustration, the duct is shown connected to a partially opened window 27 in the wall 28 of the enclosure. The fresh air is drawn in through duct 26 and through filter 29, as by the fan 30, driven by motor 31.

The function of the fan 30 is to provide a positive supply of fresh air to the enclosure, notwithstanding such difference in static pressure as may exist between the enclosure and the outdoors. Accordingly, fan 30 is designed to run at comparatively high speeds, in order that it may overcome a relatively low outdoor static pressure. High speed fans are noisy in operation, however. Thus, applicant provides a sound absorbing system in the base of unit 12 to deaden the sound of the fans. The sound absorber consists of a series of fibre baffles 32, in the sealed casing of the unit 12, which provide a tortuous path for the air. Deflector plates 33 distribute the air discharged by the fan 30 throughout the width

of the unit 12. The air then passes through the sound-absorbing baffle arrangement to the rear of unit 12, and is discharged into connecting duct 34.

From duct 34, the fresh air passes into distributing duct 35 in unit 11. As illustrated, this distributing duct has a discharge opening 36 extending substantially throughout the length of unit 11. It is to be noted that the fresh air is introduced into unit 11 above the recirculated air fans 13. These fans, then, are not required to handle both return and fresh air, as in the conventional unit, but return air only. Thus, the total volume of air passing through the unit 11 to the enclosure is not that handled by the fans 13 alone, but that handled by the fans 13 and the fan 30, so that the total air capacity of the unit 11 is increased.

Generally, the return air is more nearly suitable for distribution to the enclosure, and requires less conditioning, than the fresh air. It is generally desirable, therefore, that practically all of the fresh air be conditioned, whereas part of the return air may be bypassed around the heat exchanger coils. Accordingly, in the preferred arrangement illustrated, the opening 36 is located under coils 21 so that substantially all of the air flowing through the opening is directed in contact with the coils 21, except in the extreme case when the dampers 25 are closed. In this arrangement, substantially all of the air flowing through the bypass is return air.

Dampers 25 are pivotally mounted and adapted to swing from a horizontal position to a position approaching vertical. When the dampers 25 are in a horizontal position, they cover the heat exchange coils 21, and prevent air from passing through the passageway in which the coils are situated. When the dampers 25 are in this horizontal position, substantially all of the air passing through the unit (both fresh and return air) passes through the chamber in which plates 22 are situated. When the dampers 25 are swung upwardly, they permit the passage of air through the passageway having coils 21. When the right hand damper 25, (as seen in Fig. 2) is raised to its maximum position, it permits maximum air flow through coils 21, and cuts off air flow through plates 22. Intermediate positions of the right hand damper 25 cause desired portions of the total air handled by the unit to pass in contact through the coils 21, and through the plates 22. Ordinarily, the dampers 25 are so adjusted that air flows through both the coils 21 and the plates 22. Because the fresh air duct 35 opens directly under the coils 21, substantially all of the air issuing from duct 35 passes upwardly through the coils 21, while the room air discharged by the fan 13, passes partly through the plates 22 and partly through the coils 21.

Should the outdoor static pressure approximate or become greater than that of the enclosure, or should the wall 28 be on the windward rather than on the leeward side of the enclosure, fan 30 would tend to supply an excessive quantity of fresh air to the enclosure. As provision against such oversupply, applicant places in duct 26 a self-regulating draft check 37, comprising a vane portion 38 and a counterweight portion 39. As air passes into duct 26 at an excessive rate, the pressure on the vane 38 tends to swing the vane shut, thus restricting the passageway and reducing the flow of air through the duct. When the pressure is relieved, counterweight 39 swings the vane open.

It will be seen, therefore, that applicant provides for the supply of a substantially fixed amount of fresh air to the unit 11, regardless of the static pressure or wind conditions outdoors. 5 The fresh air is mixed in the unit 11 with the return air in predetermined proportions, and the mixture, suitably conditioned, is discharged into the enclosure through the grille 40. A damper may be provided in the fresh air intake for varying the fresh air supply.

As illustrated and described, the ventilating and conditioning units are housed in the same casing. It will be understood, however, that the outer casing 10 is merely decorative and, if 15 desired, may be dispensed with. Further, the two units need not be adjacent each other, but, if desired, may be positioned in different parts of the enclosure or building served. Again, the unit 12 may be designed to serve a plurality of 20 conditioning units 11. Thus, duct 34a, shown in dot and dash lines in Fig. 1, may convey fresh air to another conditioning unit remote from the unit 12 illustrated, or to a series of remote conditioning units.

25 In the alternative form of the invention illustrated in Fig. 4, the high speed fan 30 is replaced by a two-stage fan 41 comprising sections 41a and 41b. The static pressure built up by a fan is a function of the speed of the fan. 30 Static pressure, however, may be built up in steps. Therefore, the two fan sections 41a and 41b, in staged or successive operation, while running at a speed considerably less than that of the fan 30, can draw in as much air against 35 a reduced outdoor static pressure as the single stage high speed fan 30. The fan 41 may be designed to operate at the same speed as the fan 13, handling recirculated air. In such case, motor 14 may serve to drive both the fresh air 40 and recirculated air fans, and motor 31 may be dispensed with. Further, when fan sections 41a and 41b operate at reduced speed, they produce only a slight amount of noise, negligible in most 45 applications. Thus, the sound absorber arrangement of Figs. 1 and 3 may also be eliminated.

Since certain changes in carrying out the

above method of operation and in the constructions set forth, which embody the invention, may be made without departing from its scope, it is intended that all matter contained in the above description or shown in the accompanying drawings shall be interpreted as illustrative and not in a limiting sense. 5

We claim:

1. In an air conditioning apparatus, a first passage, conditioning means in said first passage, 10 a second passage adjacent said first passage, means including a duct below said first passage and running substantially lengthwise thereof for routing a first volume of fresh air through said first passage only, in contact with said conditioning means, and means for supplying a second 15 volume of return air to said second passage, and means for supplying said first and second air volumes to an enclosure served by the apparatus. 20

2. In an air conditioning unit, a casing, means within the casing for forming within the casing a first passageway and a second passageway, heat exchange means in said first passageway, means for drawing air from a first source and 25 for routing said air through said first passageway exclusively, means for drawing air from another source and routing said last mentioned air through said first and second passageways, and means for supplying to the enclosure served 30 by the unit air from said first and second passageways.

3. In an air conditioning apparatus, a first passage, conditioning means in said first passage, 35 a second passage adjacent said first passage, means including a duct below said first passage and running substantially lengthwise thereof for routing a first volume of fresh air through said first passage only, in contact with said conditioning means, means for supplying a second 40 volume of return air to said second passage and said first passage, and means for supplying said first and second air volumes to an enclosure served by the apparatus.

VENTILATING AND CONDITIONING SYSTEM. Patent dated May 31, 1938.
Disclaimer filed September 30, 1939, by the assignee, *Carrier Corporation*.

Hereby enters this disclaimer to claim 2 of said specification, except as relating to a unit comprising two adjacent horizontally extending passageways through each of which air is caused to flow in a vertical direction, the air circulated through said first passageway by-passing said second passageway, and the air passing through said second passageway by-passing said first passageway, only one of said passageways containing heat exchange means for thermal treatment of air circulated through said unit.

[Official Gazette October 24, 1939.]

It will be seen, therefore, that applicant provides for the supply of a substantially fixed amount of fresh air to the unit 11, regardless of the static pressure or wind conditions outdoors. 5 The fresh air is mixed in the unit 11 with the return air in predetermined proportions, and the mixture, suitably conditioned, is discharged into the enclosure through the grille 40. A damper may be provided in the fresh air intake for varying the fresh air supply.

As illustrated and described, the ventilating and conditioning units are housed in the same casing. It will be understood, however, that the outer casing 10 is merely decorative and, if 15 desired, may be dispensed with. Further, the two units need not be adjacent each other, but, if desired, may be positioned in different parts of the enclosure or building served. Again, the unit 12 may be designed to serve a plurality of 20 conditioning units 11. Thus, duct 34a, shown in dot and dash lines in Fig. 1, may convey fresh air to another conditioning unit remote from the unit 12 illustrated, or to a series of remote conditioning units.

25 In the alternative form of the invention illustrated in Fig. 4, the high speed fan 30 is replaced by a two-stage fan 41 comprising sections 41a and 41b. The static pressure built up by a fan is a function of the speed of the fan. 30 Static pressure, however, may be built up in steps. Therefore, the two fan sections 41a and 41b, in staged or successive operation, while running at a speed considerably less than that of the fan 30, can draw in as much air against 35 a reduced outdoor static pressure as the single stage high speed fan 30. The fan 41 may be designed to operate at the same speed as the fan 13, handling recirculated air. In such case, motor 14 may serve to drive both the fresh air 40 and recirculated air fans, and motor 31 may be dispensed with. Further, when fan sections 41a and 41b operate at reduced speed, they produce only a slight amount of noise, negligible in most 45 applications. Thus, the sound absorber arrangement of Figs. 1 and 3 may also be eliminated.

Since certain changes in carrying out the

above method of operation and in the constructions set forth, which embody the invention, may be made without departing from its scope, it is intended that all matter contained in the above description or shown in the accompanying drawings shall be interpreted as illustrative and not in a limiting sense. 5

We claim:

1. In an air conditioning apparatus, a first passage, conditioning means in said first passage, 10 a second passage adjacent said first passage, means including a duct below said first passage and running substantially lengthwise thereof for routing a first volume of fresh air through said first passage only, in contact with said conditioning means, and means for supplying a second 15 volume of return air to said second passage, and means for supplying said first and second air volumes to an enclosure served by the apparatus. 20

2. In an air conditioning unit, a casing, means within the casing for forming within the casing a first passageway and a second passageway, heat exchange means in said first passageway, means for drawing air from a first source and 25 for routing said air through said first passageway exclusively, means for drawing air from another source and routing said last mentioned air through said first and second passageways, and means for supplying to the enclosure served 30 by the unit air from said first and second passageways.

3. In an air conditioning apparatus, a first passage, conditioning means in said first passage, 35 a second passage adjacent said first passage, means including a duct below said first passage and running substantially lengthwise thereof for routing a first volume of fresh air through said first passage only, in contact with said conditioning means, means for supplying a second 40 volume of return air to said second passage and said first passage, and means for supplying said first and second air volumes to an enclosure served by the apparatus.
